UNITED STATES PATENT OFFICE.

BENJAMIN F. BAIN, OF PITTSBURGH, PENNSYLVANIA.

TOY.

1,314,238.

Specification of Letters Patent. Patented Aug. 26, 1919.

Application filed March 28, 1918. Serial No. 225,203.

To all whom it may concern:

Be it known that I, BENJAMIN F. BAIN, a citizen of the United States, residing at Pittsburgh, in the county of Allegheny and State of Pennsylvania, have invented certain new and useful Improvements in Toys, of which the following is a clear and exact description taken in connection with the accompanying drawings.

10 The present invention relates to new and useful improvements in toys, and has reference more particularly to that type in which marbles or portions of material such as for example, sand, are intermittently delivered 15 to and employed to actuate the toy by gravity. It has for its primary object to provide a toy having an elevator bucket constructed and arranged to be automatically raised and lowered toward and from the 20 loading chute, together with means for positively ejecting the load carried by the bucket when in lowered position, thereby releasing the bucket which is again hoisted, to receive another load. A further object of the 25 invention consists in arranging certain component parts of the toy so that it may be readily folded in a comparatively small space when not in use, and as easily packed. These, together with such objects as may 30 hereinafter appear, or are incident to my invention, I attain by means of a construction illustrated in preferred form in the accompanying drawings, wherein—

Figure 1 is a side elevation of a toy embodying my invention, and in which the bucket is shown intermediate its raised and lowered positions; Fig. 2 represents a rear elevation of the same, the inclined chute being shown in transverse section taken along the line II—II of Fig. 1; Fig. 3 is a transverse section taken through the supporting frame of Fig. 1 along the line III—III, looking in the direction of the arrows in said figure; Fig. 4 represents a detailed sectional view of the basal portion of the toy illustrating the means for relieving the bucket of its load; and Figs. 5 and 6 are sectional views of the inclined chute and discharging mechanism.

50 Referring to the drawings, the base 7 is provided with two pairs of standards 8 and 8^a, circular in cross-section, and disposed in parallelism, each pair of standards preferably comprising a single rod bent at its central portion to assume the position as shown.

The bent central portion in each case thus forms a top member 9 and both project outwardly in a horizontal plane to support a cross-head 10 formed with depending terminal portions 11 slotted so that these portions may be sprung over rebent portions 12 of the top members 9, the lower ends of the standards being secured to the base 7 and thereby producing a rigid frame or support.

The numeral 13 designates an inclined chute, channel shaped in cross-section, whose lower inner end is provided with a downwardly opening discharge hopper 14 disposed beneath the cross-head 10. The inner end of the chute extends intermediately of two of the standards and is supported in its inclined relation by a pair of spring arms 15 which have their lower ends pivotally carried by a bar 16 mounted on said standards, and have their upper ends formed with abutments that may be sprung into apertures provided in the side walls of the chute 13. As a further means of support the inner end of the chute is provided with outwardly projecting ears 17 terminally formed with key-hole slots 18 and through which extends a vertically disposed thin cross-bar 19 extending between the other two standards. The numeral 20 designates a revolvable member which is carried on an axle or shaft 21 supported preferably by the U-shaped standard 22, riveted or otherwise attached at its bent basal portion to the head 10.

The numeral 24 indicates an elevator bucket which is provided at each side with spaced guide flanges 25, so arranged that the bucket may receive guided movement from the standards 8 in its slidable ascent thereon toward the discharge hopper 14 and in its descent therefrom toward a positive ejecting member 26 disposed directly in the path of bucket travel. The bucket is provided with a bail arm 27 and is flexibly connected by a cord 28 to a counterweight 29 which is also flanged at its sides at 30 for guided travel upon the standards 8^a in a direction opposite to that of the bucket. Preferably the cord is passed through the slots 23 in the cross-head and about the revoluble member 20 in order to assure ease and guidance in the raising and lowering of the bucket.

Referring now more particularly to Figs. 1, 3 and 4, it will be seen that I provide the

base with a short downwardly inclined chute 31 disposed at one side of the ejecting member 26 and within the pairs of standards 8 and 8^a, the direction of inclination being 5 opposite to that of the upper inclined chute 13, and leading to a storage pocket 32 which is formed by a U-shaped hoop member 33 whose spring arms, toward their ends, are apertured in order to detachably engage 10 abutments 34 formed on the exterior face of the base side walls 35. This member 33 virtually constitutes a portion of the base, and extends below the upper inclined chute 13 to provide against any adventitious overbal- 15 ancing of the toy.

As indicated in Figs. 5 and 6, a series of marbles may be, and is preferably, employed to operate the bucket, though it will be understood that devices or material other 20 than marbles may be used without in any way departing from the spirit and scope of my invention. Normally the marbles 40 in the chute 13 are held in readiness for action by a discharge control means positioned in 25 the hopper, said means comprising a pivoted hoop 36 having opposed arms 39 adapted to first hold and then receive the marbles in succession, as indicated in Figs. 5 and 6, and a trigger or trip member 37 depending externally of the hopper in position to be actuated by the impact of the bucket upon elevation of the latter by the counterweight 29, the body portion 38 of the trigger forming the pivot pin of the hoop and being mounted 30 for oscillatory movement from the side walls 35 of the chute, as shown.

The bucket has its inner side open and is formed in its base with an opening 41 in which the marble rests during the descent 40 of the bucket, so that when the bucket reaches the position shown in Fig. 4 the member 26 in passing through opening 41 operates through the instrumentality of its inclined finger 26^a to eject the marble 45 through the opening side of the bucket onto the track 31 and from thence into the storage pocket 32, where the marbles are successively stored in readiness for the reloading of the inclined upper chute 13.

With the parts positioned as described and shown, and assuming that a number of marbles have been placed in the chute 13 in order to operate the toy, the first marble of 55 the series will be encircled and held in the passage 14^a by the discharge control member 36, as shown in Fig. 6, while the trigger 37, occupying the inclined position indicated in Fig. 1, is in readiness to be tripped by the arm 27 in the upward flight of the bucket. 60 Upon being tripped the member 36 moves vertically on its axis 38 and frees the marble in the passage, which, under the guidance of the inclined wall 14^a is directed in movement toward and into the bucket when 65 it rests, during the ensuing descent of the

bucket, in the smaller opening 41. During the descent of the bucket the counterweight 29 is in process of being hoisted, while the discharge member 36 has again received and holds the next marble in succession in 70 position in the discharge passage. Upon the ejection of the marble from the bucket in the manner heretofore described, the counterweight in turn descends and the bucket rises to again actuate the discharge control, 75 as before, and this automatic movement of the bucket may be continued so long as a marble remains in the loading chute. During the actuation of the discharge member 36 immediately subsequent to the release of 80 a marble, it moves on a short arc with sufficient force to administer a kick to the marbles in reserve, conferring a measure of mobility upon them to insure that without fail the lowest marble in the series will inevitably gravitate into said member in readiness for discharge.

As previously indicated, devices and granular material, other than marbles, may be substituted, and have heretofore been employed in gravity operated toys as is well known to those skilled in the art, and accordingly I wish it to be understood that any use of the term "material" by me includes marbles or any equivalent means 95 which may be used to impart movement by gravity to the bucket. Neither do I intend to restrict myself to the exact construction of details or to the precise arrangement of the various parts as modifications and adaptation thereof may be made without in any way departing from the spirit and scope of the claims.

As a further advantageous feature of my invention projecting parts of the toy may 105 be readily dissociated in order to attain a small compass for purposes of packing for shipment or storage when not in use. For example the "pocket" hoop 33 may be disengaged from the lugs 34 by simply spreading the spring arms 33 sufficiently apart to clear them. Similarly, the cross-head 10 may be easily removed or detached from the supporting frame by slightly springing 110 apart the flanges 11 so that the slots therein are freed from the rebent portions 12. Upon disengagement of the cross-head, the inclined chute 13 may be easily removed by first releasing the pivoted arms 15 and then by moving the chute on an arc in an upward 115 direction between the standards until it assumes a vertical position whereupon the key-hole slots 18 permit disengagement from the vertical cross-bar 19.

While forming no part of this invention, the oscillatory movement imparted to the wheel 20 by the opposing movement of the bucket and counterweight may be advantageously converted into a continuous forward rotary movement of a wind-mill 125 130

42, the means by which this is accomplished being incorporated in my co-pending application, Serial No. 211,342.

What I claim is:

- 5 1. A mechanical toy comprising in combination, a base, a pair of inverted substantially U-shaped supporting guideways having their upper ends bent laterally, a cross-head provided with slotted, terminal portions adapted to be sprung over the laterally bent ends of the supporting guideways, the cross-head having a revoluble member mounted thereon, a flexible driving member for the revoluble member, and devices connected with said driving member movable in the supporting guideways. 10
2. A mechanical toy comprising a base and a frame comprising two pairs of upright rods having their lower terminals mounted on said base, the rods of each pair having their upper ends bent and joined, a cross-head detachably engaging said bent and joined ends and provided with a revoluble member, a bucket and a counter-weight supported by said revoluble member and mounted for opposed vertical movement on said rods, a removable inclined chute having its inner end disposed immediately below said cross-head and positioned between the said 15 pairs of rods, said chute adapted upon removal to swing upwardly and intermittently past said joined ends upon detachment of said cross-head from the frame, discharge controlling means for said chute inner end whereby said chute delivers to the bucket when the latter is elevated by the counter-weight, and a flexible connection for the bucket and counter-weight extending through said bent upper ends and past said discharge 20 controlling means.
3. In a toy, the combination of a frame comprising opposed pairs of upright rods, the rods of each pair joined at their upper ends and bent laterally, a cross-head therefor having slotted dependent marginal flanges designed to be sprung over said bent upper ends and provided with a revoluble member, and actuating means for said revoluble member including devices oppositely 25 slidable on said pairs of rods and a flexible connection therefor extending through the slots in the cross-head.
4. In a toy, the combination of a frame comprising opposed pairs of upright rods, the rods of each pair joined at their upper ends and bent laterally, a cross-head therefor having slotted dependent marginal flanges designed to be sprung over said bent upper ends and provided with a revoluble member, and actuating means for said revoluble member including devices oppositely 30 slidable on said pairs of rods and a flexible connection therefor extending through the slots in the cross-head.
5. A mechanical toy comprising in combination, a base, a pair of inverted substantially U-shaped supporting guideways, a detachable cross-head provided with terminal portions adapted to be sprung over the ends of the U-shaped supporting guideways, the cross-head having a revoluble member mounted thereon, a flexible driving member for the revoluble member, and devices connected with said driving member movable in the supporting guideways. 35
6. A mechanical toy comprising in combination, a base, a pair of inverted, parallel, substantially U-shaped guideways, a cross-head, having a revoluble member mounted thereon, at the top of said guideways, a flexible driving member for the revoluble member, a counter-balance and a bucket connected with said driving member and movable one in each of the supporting guideways, a removable inclined chute having its inner end disposed below the cross head, discharge 40 controlling means for said chute inner end, and a hopper portion depending from the chute inner end having a laterally inclined delivery channel directed to deliver between the sides of the guideway to the bucket when the latter is elevated by the counter-balance. 45
7. A toy comprising in combination a base, a pair of inverted substantially U-shaped supports, a cross-head provided with terminal portions adapted to be sprung over the upper ends of the inverted U-shaped supports, a counter-weight and a bucket movable vertically one on each of the U-shaped supports, the bucket having an opening in the bottom thereof, a chute adapted to deliver to the bucket when in upper position, and ejecting means on the base adapted to operate through the bottom of the bucket when the latter descends. 50
